COKE OVEN DOOR

Filed Aug. 20, 1927

INVENTOR
Carl Otto

BY
W. J. Bissinger
ATTORNEY

UNITED STATES PATENT OFFICE

CARL OTTO, OF ESSEN-RUHR, GERMANY

COKE OVEN DOOR

Application filed August 20, 1927, Serial No. 214,404, and in Germany August 21, 1926.

This invention relates to self-tightening coke oven doors.

It is well-known, to use an asbestos cord to tighten the door of the chambers of coke ovens, where self-tightening doors are provided for, the asbestos cord being pressed from the outside into a wedge-shaped joint formed between the door and the door frame, by means of a pressure device. The structures hitherto proposed for this purpose mostly suffer from the drawback, that the applying of the door with the accompanying tightening some of the packing means is very cumbersome and requires much time, and does not afford a reliable gas-tight closure of the oven chamber. The invention has for its object to obviate these drawbacks, by providing a construction which secures an easy placing of the chamber door and a reliable gas-tight closure. To this end, in accordance with the invention a plurality of bolts are arranged on the outer side of the door, which bolts engage, when the door is set in, pressure pieces having inclined faces provided on a fixed part of the oven, so that the door is pressed automatically on the door frame and the pressure is transmitted to the packing means.

In order to permit the invention to be more easily understood, a preferred embodiment of the same is illustrated by way of example in the drawings which accompany and form part of this specification. In these drawings:

Fig. 1 is a vertical section through a self-tightening coke oven door.

Fig. 2 is a horizontal section on line 2-2 of Fig. 1,

Fig. 3 is a detail of Fig. 1, on an enlarged scale,

Fig. 4 is a detail of a somewhat modified form of a device for tightening home the packing means, on an enlarged scale, and

Fig. 5 is a horizontal section on line 5-5 of Fig. 4.

A coke oven door *a*, designed as a stopper door, rests in the usual manner in a door frame *b*, when in closing position. The door *a* has lateral flanges *a*¹ of a configuration such as to form with frame *b* an outwardly open

wedge-shaped groove, see Fig. 2. A packing means, e. g. an asbestos cord *c*, is loosely embedded in this groove. An adjusting device serves to locally tighten the yielding packing means *c* by means of a pressure frame mounted in front of it, this adjusting device substantially consisting of two vertical sheet metal strips *d*, mounted on the outer side of the door *a*, see Fig. 2, bolts *e*, angular levers *f*, and inclined pressure pieces *g*, inclined toward the oven. The strips *d* have a plurality of slots *d*¹ engaged by a corresponding number of bolts *e*, which thus may vertically shift within determined limits. The outer ends of the bolts *e* project laterally beyond strips *d* and abut on the inclined pressure pieces *g* fixed on the tie rails *h* of the oven on two opposite sides of the door, Fig. 2. When the bolts *e* are moved downward against the inclined faces of pressure pieces *g*, e. g. by blows of a hammer, a transmission of the pressure takes place to the angular levers *f*. The latter are fixed by pins *i* on outer ribs of the door *a* and may rock horizontally about bearings *k*. Through an intermediate piece *f*¹ hinged on them, the levers *f* abut on a tightening frame *f*², which is arranged in front of the packing means and transmits the pressure thereto, thus providing a reliable gas-tight closure.

As illustrated in Figs. 4 and 5, the frame *f*² may be subdivided so as to form individual elements interconnected by straps *f*³ and bails *m*, in order that local inaccuracies of the abutment surface of the packing means *c* between door *a* and frame *b* may be compensated for. The packing means *c* is pressed inward, in this case too, by bolts *e* that engage the back of the bails *m*, so that a downward motion of the bolts *e* may be caused by hammer blows thereon or on an iron hook loosely attached thereto. A clamping action of the bolts *e* on the inclined pressure pieces *g* and thus a tightening of the packing means *c* between door *a* and frame *b* is thereby obtained.

To secure the door *a* in closing position, the sheet metal strips *d* arranged on the outer side of door *a* are provided with a bolt *n* and another bolt *o* loosely resting in slots *d*². The ends of the bolts *n* and *o* are guided by inclined pressure pieces *p*, provided on the tie

rails *h* of the oven, when the door is in place, in such a manner, that the latter is automatically pressed against the frame *b*.

When the door *a* is to be placed, this is effected by forwarding the door toward the aperture of the chamber by means of a lifting device, and then lowering the door to such an extent by operating an adjusting device that the bolt *n* firmly rests on the inclined pressure pieces *p*. The bolt *n* is thereby clamped on these faces and the door *a* is pressed against the door frame *b*. The bolt *o* as well as the bolts *e* intended to tighten the packing means *c*, lower themselves by their own weight onto their respective inclined pressure pieces *g* fixed on the oven, to such an extent, that the door and the packing means are tightened automatically. Preferably all the bolts are then driven home by hammer blows. Instead of a hammer, any suitable tightening means may be made use of.

When the door *a* is to be opened, a lifting device is run opposite the door and by manipulating an adjusting device *t*, all bolts are loosened simultaneously and the door *a* is lifted. After all bolts have been lifted so far that they are located above the upper edge of the inclined pressure pieces, the door *a* is ready to be removed.

What I claim and desire to secure by Letters Patent, is:—

1. In a coke oven having a door frame, a door within said frame, yielding packing means between the door frame and door, rigid inclined pressure pieces arranged on fixed parts of the oven on two opposite sides of the door frame and inclined toward the oven, horizontal lateral projections arranged on said door and adapted to engage and be moved along said inclined pressure pieces and means for transmitting pressure from said projections to said packing means.

2. In a coke oven having a door frame, a door within said frame, yielding packing means between the door frame and door, rigid inclined pressure pieces arranged on fixed parts of the oven on two opposite sides of said door frame and inclined toward the oven, a member adapted to shift vertically on said door, and lateral projections arranged on said member adapted to engage and be moved along said inclined pressure pieces and means for transmitting pressure from said projections to said packing means.

3. In a coke oven having a door frame and a door within said frame, a packing means embedded in a joint formed between the door frame and door, rigid inclined pressure pieces arranged on fixed parts of the oven on two opposite sides of the door frame and inclined toward the oven, members adapted to vertically shift on said door in parallel to one another, lateral projections arranged on said members and adapted to engage and move

along said inclined pressure pieces, tightening means adapted to press against and tighten the packing means in said joint and connections between the tightening means and some of said lateral projections for transmitting pressure to the tightening means. 70

4. In a coke oven having a door frame, a door within said frame, a packing means embedded in a joint formed between the door frame and door, rigid inclined pressure pieces arranged on fixed parts of the oven on two opposite sides of said door frame and inclined toward the oven, members adapted to vertically shift on said door in parallel to one another, said members provided with vertical slots arranged in pairs at common levels, horizontal bolts extending through the slots, laterally projecting beyond said members and adapted to engage and move along the inclined pressure pieces, tightening means adapted to press against and tighten the packing means in said joint and connections between the tightening means and some of said bolts. 75

5. In a coke oven having a door frame, a door within said frame, a packing means embedded in a joint formed between the door frame and door, rigid inclined pressure pieces arranged on fixed parts of the oven on two opposite sides of said door frame and inclined toward the oven, members adapted to vertically shift on said door in parallel to one another, said members provided with vertical slots arranged in pairs, at common levels, horizontal bolts extending through the slots, laterally projecting beyond said members and adapted to engage and move along the inclined pressure pieces, a tightening frame arranged between the horizontal bolts and the packing means and connections mounted for rocking motion and abutting on the horizontal bolts and the last-named frame for transmitting pressure from said bolts to the frame. 90

6. In a coke oven having a door frame, a door within said frame, a packing means embedded in a joint formed between said door frame and door, rigid inclined pressure pieces arranged on fixed parts of the oven on two opposite sides of said door frame and inclined toward the oven, members adapted to vertically shift on said door in parallel to one another, said members provided with vertical slots arranged in pairs at common levels, horizontal bolts extending through said slots, laterally projecting beyond said members and adapted to engage and move along said inclined pressure pieces, a tightening frame arranged between the horizontal bolts and the packing means, said frame consisting of a plurality of yieldingly interconnected elements, and connections between said last-named frame and some of said horizontal bolts. 100

7. In a coke oven having a door frame, a

door within said frame formed to provide a joint between the door and frame, a packing means embedded in the joint, rigid inclined pressure pieces arranged on fixed parts of the
5 oven on two opposite sides of the door frame and inclined toward the oven, members adapted to shift vertically on said door in parallel to each other, said members provided with vertical slots arranged in pairs at common
10 levels, horizontal bolts extending through said slots, projecting laterally beyond said members and adapted to engage and be moved along said inclined pressure pieces, a tightening frame arranged between the horizontal bolts and the packing means, said frame consisting of a plurality of yieldingly interconnected elements and a plurality of bails, each pivotally connected to two neighboring frame elements of said last-
15 named frame and forming connections between said bolts and last-named frame.

In testimony whereof, I have signed my name to this specification.

CARL OTTO.
